UNITED STATES PATENT OFFICE.

CLIFTON CHISHOLM, OF CLEVELAND, OHIO, ASSIGNOR TO THE AMERICAN MULTIGRAPH COMPANY, OF CLEVELAND, OHIO, A CORPORATION OF OHIO.

IMPLEMENT FOR LOCKING PRINTING STRIPS.

Application filed September 25, 1924. Serial No. 739,946.

I have devised a system of printing wherein embossed strips are removably mounted on a suitable holder, as for instance on an address plate or a flexible blanket adapted 5 for mounting on a rotary drum. Such plate or blanket has rows of projections which the embossed strips overlie, and on which they are retained by inwardly turned edge flanges on the strips extending beneath over- 10 hanging portions of the projections. This provides a simple printing form. It is desirable however, that means be provided to prevent the strip shifting longitudinally on the holder.

15 The present invention comprises a very simple implement for inwardly indenting of the embossed strips to lock them onto their holders to prevent longitudinal shifting. Briefly, the implement comprises a die head 20 having a pair of inclined jaws which engage opposite edges of the strip, and means for delivering a blow on the head to indent such edges. The means for delivering the blow may well comprise a spring adapted to be 25 compressed against a retracted hammer which is then suddenly released, to cause the hammer to deliver a blow to the die and thence to the strip edges.

30 My invention is hereinafter illustrated in the drawings hereof, and is hereinafter more fully explained and the essential characteristics are summarized in the claims.

In the drawings, Fig. 1, is a longitudinal central section of an implement corresponding 35 to the present invention; Fig. 2 is a perspective of a portion of a blanket with an embossed strip mounted thereon, showing the implement in position for action; Fig. 3 is a diagrammatic view illustrating the implement as first applied to the strip; Fig. 4 illustrates it after the die has impressed the strip; Fig. 5 is a perspective of the strip showing the indenting effect of the die.

40 As shown in the drawings, the die head 10 is a small block of metal having at its lower end a pair of projecting jaws 11 leaving a wide groove or channel 12 between them. The inner faces of the jaws are inclined outwardly toward their free edges as shown in 45 14, while the outer faces are inclined inwardly, so that the jaws come substantially to sharp or very narrow edges. The distance between the two inclined edges 14 of the jaws is selected with reference to the width of the

embossed strip so that these inclined faces 55 are adapted to engage the edges of the strip and thus a blow on the die will indent the edges of the strip inwardly.

In Figs. 2, 3, and 4, A indicates a flexible blanket, address plate or other supporting 60 member. This plate is preferably of sheet metal carrying on its surface rows of elevated buttons or projections *a*, struck up from the plate. Preferably between the projections are corrugations *a*¹, also struck up 65 from the plate. In the direction of the rows, the buttons are connected with the tops of the corrugations but transversely of the row the arcuate edges of the buttons are free 70 from the plate and stand some distance above it. Such a plate is more fully described and claimed in patents numbered 1,438,584 and 148,582 granted to my assignee The American Multigraph Company, December 12th, 1922, on applications of Wm. J. Demming and Burnie J. Craig respectively.

The embossed strips are indicated by B. Each strip has struck up on it a row of printing characters designated *b*. The edges of the strip are curled or flanged as in *b*¹. 80 The strips are thus adapted to overlie the projections and be retained thereon by reason of the flanges of the strips extending beneath the overhanging edges of the projections.

As is apparent from Fig. 2, the length of 85 the jaws 11 acting longitudinally on the strip is greater than the distance between the extreme points of the buttons *a*, so that, no matter in what region the jaws are placed against the strip, they will act on it for a 90 distance sufficient to cause the strip to bind at least against one of the buttons and sometimes against two of them. Figs. 4 and 5 show at *b*² the inwardly indented region of 95 the strip which thus binds against the button edges. It will be seen from Fig. 4 that the outer surface of the strip, which is normally rounded, has been flattened at the jaws complementarily to the jaw surface, while Fig. 5 shows that the indentations extend longitudinally for a considerable distance. I use this terminology "considerable distance" as signifying an extent sufficient to reach from one button to the next.

The embossed strips are ordinarily made 105 of aluminum and I have found that a comparatively light blow upon the head is sufficient to indent the strips to cause them to

bind on the buttons. While the blow must be of sufficient force to effect the indentation, it should not be excessive, as that might otherwise distort the strip. Accordingly, it 5 is desirable to provide means for delivering a constant blow. I have found it very satisfactory to provide a hollow handle in which the shank of the head is slidably mounted and provide in this handle a slidable hammer 10 block acted on by a spring which is compressed when the handle is shoved inwardly and then suddenly released to cause the hammer to deliver a constant blow to the die head. Such mechanism is shown in Fig. 1 15 and will now be fully described.

In Fig. 1, 20 indicates the barrel of a handle which is closed at its upper end by a suitable cap 21, having a threaded extension 22, screwing into the end portion of the barrel 20. At its lower end, the barrel has an internal thread 23, in which screws a reduced extension 24 on the hammer guiding portion 25 of the handle. The die head 10 has a shank slidably mounted in this handle extension 25. I have shown the head 10 as having a threaded stud 15 screwing into a rod 30 which in operation constitutes a rigid shank for the head. This shank is slidably mounted within the handle portion 25 and 30 has a collar 31 occupying a larger bore 26 in the handle. The shank also carries a laterally projecting pin 33 occupying a slot 28 in the handle extension. Accordingly, the shank may slide freely in the handle, but 35 cannot turn with reference thereto; its outward and inward movements are limited by the collar 31 and die head 10 respectively.

The shank 30 with its head 10 is normally held in the extended position shown in Fig. 40 1, by means of the comparatively light compression spring 40 which lies within the bore 26, around the portion 35 of the shank and bears at its lower end against the collar 31 and its upper end against a slidable impact 45 block or hammer 50 to be described. Above the shank portion 35 is a reduced portion constituting an axially extending pin 37, and the hammer has an axial bore which loosely surrounds the pin. This hammer is freely 50 slidable within the barrel 20. It has a lateral recess 41 in which is mounted a dog 52 adapted to overhang the top of the shank pin 37. This dog is normally pressed inwardly into this position by a spring 53 carried by the hammer, and thus retains the 55 hammer in raised position.

The bore 55 of the hammer which, as stated, is occupied by the shank pin 37 below the dog 52 is also occupied above the dog by 60 a pin 60 carried by and projecting inwardly from the stationary head 21. A comparatively stiff compression spring 70 occupies the space between the hammer and the head 21, being mounted with the barrel and 65 around the pin 60. The pin 60 normally

stands some distance above the dog 52. This dog has an inclined inner face as shown in 57 which may be engaged by the inner edge of the pin 60 and cammed backwardly thereby to clear the shank pin 37.

In use, the implement with the parts in 70 position as shown in Fig. 1, is placed over the strip to be indented with the jaws engaging opposite edges thereof, and then the handle is pressed downwardly toward the strip. In this movement the hammer cannot move downwardly because the dog 52 engages the top of the shank extension 37, thus providing a continuous rigid strut from the embossed strip to the compression spring 70. 80 Accordingly, this downward movement compresses this spring 70 until the pin 60, moving inwardly in the bore 55 of the hammer, engages the incline 57 of the dog 52 and cams that dog outwardly to clear the shank pin 37. As soon as this takes place the hammer 85 is free to move and is forcibly moved downwardly by the compressed spring 70, thus delivering a sharp blow against the shoulder 38 where the shank pin 37 joins the larger 90 shank pin 35. This blow is delivered through the shank to the die head and thence to the embossed strip. In this movement the spring 40 is incidentally compressed a small amount, but this spring is light enough, so 95 that it opposes no material resistance.

It will be seen that the operation of the 100 tool is very simple. It is grasped in the hand and placed with the jaws in the opposite sides of the embossed strip and the handle placed toward the strip until the indenting blow is delivered to the strip. The inward incline of the outer edges of the jaws 105 enables these jaws to engage a strip even though another strip is mounted very close to it, as illustrated in Figs. 3 and 4. The width and depth of the groove 12 in the die head is sufficient so that it clears the embossed characters on the strip so that they 110 cannot be injured by the operation. I have found that these indenting blows, delivered by a constant spring force, on the edges of the strip, while they distort the edges inwardly sufficiently to bind on the buttons have 115 no effect in bending the intermediate portion of the strip, and thus do not in any manner distort or interfere with the printing characters on the strip.

Attention is called to the fact that my application No. 50,155 filed August 14, 1925 120 and now issued as Patent No. 1,651,185, which is a continuation in part of this application, claims the method of binding strips on their holders as illustrated herein by means of delivering blows to their edges to indent such edges without disturbing the printed surface. Such method may be carried out with the assistance of the implementation of the present application or by other devices.

Having thus described my invention, I claim:—

1. An implement of the character described comprising a barrel, a movable hammer therein, a compression spring adapted to act on the hammer, a head having a pair of separated jaws having inclined inner faces adapted to engage opposite edges of an embossed strip, and means whereby inward movement of the barrel first compresses the spring, while the hammer is locked and then releases the hammer to deliver a blow to the head.
2. In a device of the character described, the combination of a die head having a pair of separated jaws with their inner faces inclined outwardly toward their free edges, the outer faces of said jaws being inclined inwardly toward said edges, and means mounted in the device, but movable with reference to the die head for delivering a blow to the die head.
3. A device for indenting the edges of a strip comprising a head having a pair of projecting jaws rigid thereon, said jaws having their inner faces inclining outwardly toward the free ends of the jaws, and the

outer faces of the jaws inclined inwardly toward their free edges, the outward and inward incline of each jaw coming substantially to a line at the edge of the jaw. 30

4. In a device of the character described, the combination with a shank, of a head having a pair of rigid jaws located parallel with each other and some distance apart, the length of said jaws in the direction of parallelism being greater than their distance apart, whereby a single pair of jaws may simultaneously engage two round buttons spaced apart and located in the same plane. 35 40

5. An indenting device adapted to bind a flanged surmounting strip on a holder having a row of spaced projections with overhanging edges, said device having opposed jaws with inclined faces adapted to engage an edge of the strip for a distance at least as great as the distance between corresponding points on two successive projections, which distance is at least as great as the distance between the jaws. 50

In testimony whereof, I hereunto affix my signature.

CLIFTON CHISHOLM.
